METHOD OF LASTING SHOES

Salvatore Cangemi, Brooklyn, N. Y., assignor to
 United Shoe Machinery Corporation, Paterson,
 N. J., a corporation of New Jersey

Application January 9, 1936, Serial No. 58,328

5 Claims. (Cl. 12—145)

This invention relates to methods of lasting shoes and particularly to methods of lasting in which the upper is cement-attached to an insole.

Objects of the invention are to facilitate the manufacture of cement-lasting shoes and particularly to facilitate the trimming away of the excess of lasting allowance.

It is common, in the lasting of shoes in which the upper is to be held in finally lasted position by cement, to wipe the upper over the bottom and insert partially driven tacks to hold the upper temporarily in position while the cement is setting. In order to hold all portions of the upper in lasted position, it is necessary to insert the tacks quite close together. It is, therefore, a further object of the invention to economize by reducing the number of tacks required to hold the upper in lasted position.

My improved method of lasting comprises progressively working successive portions of a cemented upper over the bottom of a last into lasted position, utilizing an abutment locally to hold the excess of lasting allowance of each portion so lasted in upright position and inserting a fastening temporarily to hold the overlasted portion of the upper against the last bottom. Preferably and as illustrated, successive portions of the shoe upper are seized and tensioned by a gripper, and a wiper is operated to wipe the lasting allowance over the bottom of the last, for example into engagement with an insole. The excess of lasting allowance is supported by the abutment in a position substantially perpendicular to the last bottom, the wiper acts to force or squeeze the upper against the abutment and into the angle between the abutment and the shoe bottom, and the driver acts to drive a tack through a hole in the wiper and through the upper close to the abutment, through the insole and into the last to hold the overlasted portion of the upper against the insole, the tack preferably being only partially driven to facilitate removal.

After the cement has set the tacks are removed and, since the excess of lasting allowance remains upstanding from the plane of the insole, the trimming away of the excess of lasting allowance is greatly facilitated; and, since the upstanding portion, that is, the excess of lasting allowance, is located at a predetermined distance, namely the width of the overlasted portion of the upper, from the edge of the shoe bottom, the overlasted portion is, after trimming, of uniform width and subsequent operations, such as filling the shoe or providing on the outsole an island to fill the space outlined by the inner edge of the

lasting allowance, are facilitated. Furthermore, since the excess of lasting allowance between each pair of tacks is bent in an upstanding position, it acts as a truss or flange to prevent the overlasted portion of the upper between the tacks from bending away from the insole and hence a less number of tacks is required to hold the lasting allowance of the upper against the insole while the cement is setting.

These and other aspects of the invention will appear more fully from the following description when read in connection with the accompanying drawing and will be pointed out in the appended claims.

In the drawing,

Fig. 1 is a perspective view of a shoe lasted in accordance with the present invention, and

Fig. 2 illustrates in side elevation the operating instrumentalities of a hand method machine equipped to practise the present invention, the shoe operated upon being shown in section.

In the practice of my improved method for cement-lasting shoes by which the excess of lasting material of the upper is left in upstanding position to facilitate trimming, a usual last is employed and the usual shoe upper assembled thereon. A usual unlined insole may be applied to the last bottom or, as illustrated, an insole the forepart of which is skeletonized may be employed, or, if desired, the upper at the forepart at least may be lasted over the bare last bottom. In such cases, however, a partial insole comprising a heel-and-shank piece is preferably employed. The shoe thus assembled is pulled over in the usual manner and the side lasting operation is performed in accordance with my invention on a machine of the hand method type such as that disclosed in Letters Patent of the United States No. 584,744, granted June 15, 1897, in the names of Ladd and McFeely. The machine, as usual, is provided with a sole rest 16, an edge gage 18, a gripper 20, a wiper 22 and a tack driver 24.

To equip the machine for practising my invention, the sole rest 16, instead of engaging the central portion of the last or insole as usual, is located at a predetermined distance from the edge gage 18 substantially equal to the width of the portion of the upper to be overlasted and is provided with a vertical face or abutment 26 against which the excess of lasting allowance of the upper is pressed when the wiper 22 reaches the limit of its movement inwardly over the shoe bottom. The face 26 is preferably in a plane substantially perpendicular to the shoe bottom in the

position of the shoe in which it is presented to the machine.

After the shoe has been assembled and pulled over as described, cement such as pyroxylin cement is applied between the layers of the lasting allowance of the upper materials, for example between the upper 12 and a lining 23, and if an insole is employed cement will be applied to the inner face of the lining 23 and to the margin of the insole 14. The side lasting operation is then performed by presenting the shoe to a machine of the kind described, the edge of the shoe being engaged by the edge gage 18 and the bottom of the shoe by the sole rest 16 at a distance from 5 the edge gage 18 substantially equal to the width of the portion of upper to be overlasted. The gripper 20 acts to updraw and overdraw a portion of the upper materials and the wiper 22 acts to wipe the tensioned upper over the shoe 10 bottom and to press or squeeze the excess of lasting allowance against the face or abutment 28 which is substantially perpendicular to the shoe bottom. Thus, the excess of lasting allowance is disposed in a position substantially perpendicular 15 to the shoe bottom. After the gripper 20 has reached the limit of its inward movement over the shoe bottom, a tack 30 is inserted by the driver 24 through the upper materials 12 and 23 and into the wood of the last 10 and, of course, 20 through the insole if an insole is employed, the tack 30 being left upstanding to facilitate removal. The operations described are performed progressively on successive portions of the upper materials until the sides of the shoe, and, if desired, the toe, are lasted as indicated in Fig. 1, where the overlasted portion of the upper is indicated by the numeral 32 and the excess of lasting allowance by the numeral 34. The heel-seat portion 36 of the upper may be lasted in the 25 usual manner with tacks 38 completely driven and clinched on the iron plate with which the heel end of the last is provided.

After the cement has set sufficiently to hold the upper in lasted position, the tacks 30 are withdrawn and the upper materials are trimmed away 45 along the line formed by the angle between the lasting allowance 32 and the excess of lasting allowance 34, an overlasted portion 32 of predetermined uniform width being thus produced.

Referring to Fig. 1, it will be seen that since the excess of lasting allowance 34 between each pair of tacks is bent into a position substantially at right angles to the overlasted portion 32 it resists bending in its own plane and forms a flange 50 or truss between each pair of tacks which tends to hold the overlasted portion of the upper 32 between those tacks from bending away from the shoe bottom and hence assists in holding the cemented surfaces tightly in contact. For this reason fewer tacks are necessary in lasting a shoe by this method than by the usual method where the excess of lasting allowance is laid flat against the shoe bottom. After trimming, the shoe may be finished by the attachment of an outsole and heel 55 in any usual or preferred manner.

Having thus described my invention, what I claim as new and desire to secure by Letters Patent of the United States is:

1. That improvement in methods of making 70 shoes which comprises applying cement to the opposed surfaces of the lasting allowance of a shoe upper assembled upon a last, progressively working successive portions of the shoe upper over the last bottom, turning each successive portion

of the excess of lasting allowance into an upstanding position with respect to the last bottom by squeezing it into contact with a face perpendicular to the shoe bottom, said face being carried by an abutment, utilizing the same face of the 5 abutment repeatedly in lasting successive portions of the upper, and inserting a temporary fastening through the overlasted upper close to the abutment in each of its successive positions, whereby the excess of lasting allowance is presented in a position substantially perpendicular 10 to the insole to facilitate its removal by a trimming operation.

2. In methods of cement-lasting shoes, that improvement which comprises providing a sole 15 rest having a face perpendicular to the lasting sole disposed in the direction of the sole margin, applying adhesive between the lasting sole and the marginal portions of the upper, progressively wiping the upper margin inwardly and squeezing 20 the excess thereof against said perpendicular face of the sole rest, and utilizing the same face of the sole rest repeatedly in lasting successive portions of the upper, whereby the excess of 25 lasting allowance is presented in a position substantially perpendicular to the insole to facilitate its removal by a trimming operation.

3. In methods of cement-lasting shoes, that improvement which comprises providing a sole 30 rest having a face perpendicular to the lasting sole disposed in the direction of the sole margin, applying adhesive between the lasting sole and the marginal portions of the upper, progressively wiping the upper margin inwardly and squeezing 35 the excess thereof against said perpendicular face of the sole rest, utilizing the same face of the sole rest repeatedly in lasting successive portions 40 of the upper, and inserting a temporary fastening through the overlasted upper close to said face in each of its successive positions whereby the excess of lasting allowance is formed to provide a truss-like flange between the fastenings.

4. That method of cement-lasting shoes in which there is utilized a hand method lasting 45 machine having instrumentalities for tensioning the upper and wiping a marginal portion thereof over an insole on a last including an abutment having a face perpendicular to the shoe bottom, which comprises the steps of applying adhesive 50 between the insole and the marginal portions of the upper, presenting said upper and insole on a last for the action of said instrumentalities, and utilizing the wiping instrumentalities to squeeze 55 the excess of lasting allowance against the perpendicular face of the abutment whereby the excess of lasting allowance is caused to remain in a position substantially perpendicular to the last bottom to facilitate trimming.

5. That improvement in methods of making 60 shoes which comprises applying cement to the opposed surfaces of the lasting allowance of a shoe upper assembled upon a last, progressively working successive portions of the upper over a last bottom, squeezing each successive portion of the excess of lasting allowance into contact with 65 a face perpendicular to the shoe bottom, said face being carried by an abutment, and utilizing the same abutment repeatedly in lasting successive portions of the upper whereby after the cement has set the excess of lasting allowance is 70 presented in a position substantially perpendicular to the insole to facilitate its removal by a trimming operation.
